LIQUID COOLING APPARATUS

Halsey W. Taylor, Warren, Ohio, assignor to
 Halsey W. Taylor Co., Warren, Ohio, a corpora-
 tion of Ohio

Application August 24, 1948, Serial No. 45,803

10 Claims. (Cl. 62—141)

1

My invention relates to liquid cooling apparatus, and more particularly to apparatus of the fountain type water cooler, and the principal object of my invention is to provide new and improved apparatus of the character disclosed.

Generally, in liquid cooling apparatus, and particularly in fountain type water coolers, a container is provided for the storage of cooled liquid, so that an ample supply of cooled liquid is on hand to meet the maximum demands.

It has been found, in storage containers of the kind mentioned, that the temperature of the body of liquid is not uniform throughout. For example, in water cooler tanks, it has been found that the water is colder adjacent to the refrigerant coils. This is caused largely by the proximity of the refrigerant coil to the outer portion of the water, and also by the fact that the thermal conductivity of water is materially less than that of metal, and accordingly there is a temperature lag between inner and outer portions of the body of water.

In some cases, increased refrigeration was tried to compensate for such temperature lag, but this only resulted in a "sweating" of the refrigerant coil caused by undue condensation of vapor, and sometimes resulted in an undesirable freezing of the liquid, especially when the demand was low.

My invention overcomes the prior art difficulties by providing means whereby the body of liquid is caused to have substantially uniform temperature. My invention further provides means for effectively distributing incoming liquid toward that surface of the container which is in contact with the refrigerant coil. Other advantages will appear from a reading of the following description.

In the drawing accompanying this specification and forming a part of this application, there is shown, for purposes of illustration, an embodiment which my invention may assume, and in this drawing:

Figure 1 is an elevational view, with parts broken away and parts in section, showing a water cooler incorporating the embodiment of my invention.

Figure 2 is an enlarged longitudinal sectional view of the liquid container.

Figure 3 is a transverse sectional view corresponding generally to the line 3—3 of Figure 2, and

Figure 4 is a plan view of a detail.

Referring to the drawing, the embodiment of

2

the invention herein disclosed is shown as applied to a drinking fountain 10 of any standard construction, although it will be appreciated that my invention has application other than that particularly disclosed.

The drinking fountain 10, as herein shown, has a water bubbler 11 connected to a control valve 12. A suitable drain 13 is provided for overflow water. The valve 12 is connected to the water cooling apparatus 14 which comprises my invention. It will be appreciated that other connections for control of certain functions of the apparatus, such as temperature and the like, are provided, but since such other connections form no part of my invention, their disclosure is believed unnecessary.

The water cooling apparatus 14 comprises a container for the water, which in the embodiment illustrated includes a closed tank formed by a cylindrical shell 15, a head 16, and a bottom 17. The head and bottom may be welded or otherwise suitably secured to the shell 15.

A refrigerant coil 18 is disposed about the exterior of the shell 15, in good thermal transfer relationship therewith. One way to establish such relationship is to wind the coil so that its convolutions have contact with the shell, and then dip the assembly into a flux and then into a hot tin bath. As best seen in Figure 2, the coil is so wound that its convolutions are slightly spaced apart, so that in case of rupture at any place along the coil, the refrigerant may escape without injuriously affecting the shell.

As best shown in Figure 1, opposite ends of the coil 18 are connected to a refrigerating unit 19 which may be of any well known make and therefore need not be specifically shown and described. Refrigerant from the unit 19 enters the lower end of the coil through conduit 20, and returns to the unit from the upper end of the coil through conduit 21.

My invention provides means for effecting good thermal transfer relationship between container 15 and the body of water therein, and comprises means which engage the container and extend into the body of water. As herein shown, such means comprise a plurality of thermal transfer elements 22 staggered axially and spaced-apart longitudinally with respect to the container.

Referring particularly to Figures 2 and 3, each element 22 is generally of star-shape, having the points of each element in contact with the container 15 and the body of each element extend-

ing radially inwardly of the container and in contact with the water therein.

Preferably, each element is formed of a flat strip of non-corrosive metal, the metal being bent to form the legs of the star, each leg being defined by generally parallel and radially extending portions 23 with a generally flat connecting outer point 24. Portions 23 of adjoining legs meet short of the center of the container, at inner points 33. The ends of the flat strip after being formed to star shape, may be overlapped, as shown at 25, and suitably connected, as for example by means of spot welding.

As seen in Figure 4, the flat strip is originally shaped so that the connecting points 24 are disposed in a circle greater than the inner diameter of the container 15, such diameter being represented by the dot-dash line 26 in Figure 4. To assemble the elements 22 with the shell 15, it is merely necessary to slightly spring each element radially inwardly, and enter it within the shell 15 to its proper position. The inherent springiness of the material will hold each element in engagement with the inner surface of the shell 15. Preferably, it is desirable to further secure each element to the shell, and this may be done by tin coating each element in place. Such tin coating may be effected at the same time the refrigerant coil 18 is secured to the shell 15.

The means for effecting distribution of incoming water, in the embodiment herein disclosed, comprises baffle means which may take the form of an imperforate disc 27, of suitable non-corrosive metal, the peripheral margin of the disc 27 being of less diameter than the inner surface of the shell 15, so as to form an annular space 28.

The conduit 29, leading from a suitable source of water supply, extends through an aperture in the head 16 and has its inner end connected to an intermediate portion of the disc 27, such as by means of brazing or the like. Preferably, the conduit 29 is also brazed to the head 16 to form a fluid-tight joint. Inwardly of the head 16, and spaced from the disc 27, the conduit 29 is formed with a series of openings 30. Incoming water flows through the openings 30 and spills over onto the disc 27, from where it flows through the annular opening 28 and downwardly of the interior walls of the water container.

It will thus be appreciated that incoming water is directed toward that part of the container which is in contact with the refrigerant coil 18, so as to effectively cool such incoming water. Further, the elements 22 will establish good thermal transfer relationship between the shell 15 and the inner portion of the body of water. The elements 22, as best seen in Figures 3, are so arranged that the legs of adjoining elements are staggered, thus causing convection currents of water to be broken up and further mixing of the water.

The conduit 31 which leads to the valve 12, is also preferably brazing or otherwise suitably connected to the bottom 17 in fluid-tight relationship. As a matter of assembly, the bottom 17 may first be welded to the shell 15, and then refrigerant coil 18 may be secured to the shell. Finally, the head 16, with baffle 27 and conduit 29 attached, may be welded to the shell to form the completed closed water tank.

From the foregoing, it will be apparent to those skilled in the art that I have accomplished at least the principal object of my invention,

and it also will be apparent to those skilled in the art that the embodiment of the invention herein described may be variously changed and modified, without departing from the spirit of the invention, and that the invention is capable of uses and has advantages not herein specifically described; hence it will be appreciated that the herein disclosed embodiment is illustrative only, and that my invention is not limited thereto.

I claim:

1. Liquid cooling apparatus, comprising: a closed tank for the liquid to be cooled, having a liquid inlet at its upper portion and a liquid outlet at its lower portion; baffle means directing inlet fluid, comprising an imperforate member spaced from the upper end of said tank and from said liquid inlet, the peripheral surface of said baffle means stopping short of contact with the inner wall surface of said tank, whereby inlet fluid enters said tank, engages an intermediate portion of said baffle means, and is directed toward and downwardly of said inner wall surface; a refrigerant coil exteriorly of said tank, in thermal transfer relationship therewith; and at least two axially staggered elements spaced apart longitudinally of said tank below said baffle means, each of a strip of sheet metal formed to generally star-shape, the outer points of each element contacting said inner wall surface, and the remainder of each element extending radially inwardly of said tank.

2. Liquid cooling apparatus, comprising: a container for the liquid to be cooled, said container having a top wall; a liquid inlet conduit extending through an aperture in said top wall; baffle means closing the inner end of said inlet conduit and spaced from the inner surface of said top wall, said inlet conduit having radially spaced apertures in its walls to provide for flow of inlet liquid laterally thereof and to the space between said baffle means and said top wall, and said baffle means being arranged with respect to said container to deflect flow of inlet liquid in a direction toward the inner wall surface of said container.

3. Liquid cooling apparatus, comprising: a container for the liquid to be cooled, said container having a top wall; a liquid inlet conduit extending through an aperture in said top wall; baffle means closing the inner end of said inlet conduit and spaced from the inner surface of said top wall, and said inlet conduit having radially spaced apertures in its wall to provide for flow of inlet liquid laterally thereof and to the space between said baffle means and said top wall, and said baffle means being arranged with respect to said container to deflect flow of inlet liquid in a direction toward the inner wall surface of said container; and means within said container establishing thermal transfer relationship between said container and the liquid within said container.

4. Liquid cooling apparatus, comprising: a container for the liquid to be cooled; a top for said container; a liquid inlet conduit extending through an aperture in said top and secured to said top; baffle means secured to the inner end of said inlet conduit and closing such end, said baffle means being spaced from the inner surface of said top, and said inlet conduit having radially spaced apertures in its wall to provide for flow of inlet liquid laterally thereof and to the space between said baffle means and said top, said top, said baffle means and said inlet conduit being assembleable as a unit with said container, and

said baffle means being arranged with respect to said container to deflect flow of inlet liquid in a direction toward the inner wall surface of said container.

5. Liquid cooling apparatus, comprising: a container for the liquid to be cooled; a top for said container; a liquid inlet conduit extending through an aperture in said top; baffle means closing the inner end of said inlet conduit and spaced from the inner surface of said top, and said inlet conduit having aperture means in its wall to provide for flow of inlet liquid laterally thereof and to the space between said baffle means and said top, and said baffle means being arranged with respect to said container to deflect flow of inlet liquid in a direction toward the inner wall surface of said container; a plurality of thermal transfer elements disposed below said baffle means in relative staggered relation, each establishing thermal transfer relationship between said container and the liquid within said container, said elements combining to break up straight-line fluid flow from top to bottom of said container; and cooling means in thermal transfer relationship with said container.

6. In liquid cooling apparatus, heat exchanging means comprising a container through which fluid is adapted to pass, and thermal transfer means providing thermal conductivity between said fluid and said container, said thermal transfer means comprising a sheet-metal member formed separately of said container and providing a star-shaped fin element assembled to position within said container wherein it is disposed edge-wise to the flow of fluid in said container and wherein the points of the star are in conducting engagement with the inner walls of said container and the remainder of the star extend radially inwardly of said container.

7. In liquid cooling apparatus, heat exchanging means comprising a container through which fluid is adapted to pass, and a plurality of thermal transfer means providing thermal conductivity between said fluid and said container, each of said thermal transfer means comprising a strip of thermal conducting material formed to star-shape, the points of each star being in conducting engagement with the inner walls of said container and the remainder of each star extending radially inwardly of said container, said thermal conducting means being disposed edge-wise with respect to each other and axially of said container with the points of one star out of alignment with the points of an adjacent star.

8. Liquid cooling apparatus comprising a container for the liquid to be cooled, an imperforate baffle extending crosswise of said container and disposed at an upper portion thereof, the peripheral edge of said baffle being spaced from the inner wall surface of said container, and a fluid inlet conduit entering said container and directed toward an intermediate portion of said

baffle, the terminal end of said conduit being closed and said conduit having radially spaced apertures in its wall and adjacent to said closed end to provide for flow of inlet liquid laterally of said conduit and radially along said baffle to the space between the peripheral edge of said baffle and the inner wall surface of said container.

9. Heat exchanging means for liquid cooling apparatus comprising a container through which fluid is adapted to pass, and thermal transfer means providing thermal conductivity between said fluid and said fluid and said container, said thermal transfer means being made of strip sheet-metal which has been formed to provide a star-shaped fin element assembleable to position within said container, said element prior to assembly with said container being formed so that said points lie in a circumferential outline greater than the outline of the inner wall surface of said container so that said element is compressed during assembly with said container and so that following assembly said points are pressed against the inner wall surface of said container.

10. Heat exchanging means for liquid cooling apparatus comprising a container through which fluid is adapted to pass, an imperforate baffle extending cross-wise of said container and disposed at an upper portion thereof, the peripheral edge of said baffle being spaced from the inner wall surface of said container, an inlet conduit entering said container and directed toward an intermediate portion of said baffle, the terminal end of said conduit being closed and said conduit having radially spaced apertures in its wall and adjacent to said closed end to provide for flow of inlet liquid laterally of said conduit and radially along said baffle to the space between the peripheral edge of said baffle and the inner wall surface of said container, and thermal transfer means within said container and below said baffle comprising a plurality of generally radially extending fins which are joined to provide a star-shaped element, the points of the star being in conducting engagement with the inner wall of said container and the remainder of the star extending inwardly of said container.
